FIG. 10.

UNITED STATES PATENT OFFICE.

ARTHUR W. SMITH, OF NEW YORK, N. Y., ASSIGNOR TO REMINGTON TYPEWRITER COMPANY, OF ILION, NEW YORK, A CORPORATION OF NEW YORK.

TYPE-WRITING MACHINE.

1,287,123.

Specification of Letters Patent. Patented Dec. 10, 1918.

Application filed April 13, 1915, Serial No. 21,005.

To all whom it may concern:

Be it known that I, ARTHUR W. SMITH, citizen of the United States, and resident of the borough of Manhattan, city of New York, in the county of New York and State of New York, have invented certain new and useful Improvements in Type-Writing Machines, of which the following is a specification.

10 My invention relates to typewriting machines and more particularly to means for controlling continuous work sheets and interleaved transfer sheets, and for effecting a relative displacement between the two; and 15 the object of said invention is to provide simple and efficient means of the character specified.

To the above and other ends which will hereinafter appear, my invention consists of 20 the features of construction, arrangements of parts and combinations of devices set forth in the following description and pointed out in the appended claims.

In the accompanying drawings, wherein 25 like reference characters indicate corresponding parts in the different views,

Figure 1 is a fragmentary, front elevation, showing the upper portion of a type-writing machine embodying my invention, 30 and with the work sheet in place.

Fig. 2 is a fragmentary, vertical, fore and aft, central sectional view of the same with the work sheet omitted.

Fig. 3 is a fragmentary, detail, perspective view showing a portion of the slide to 35 which the transfer sheets are connected, as well as some of the associated parts.

Fig. 4 is a fragmentary plan view, with parts broken away, of the construction, 40 represented in Fig. 2.

Fig. 5 is a fragmentary, central, fore and aft, vertical sectional view of the carriage and some of the associated parts, the view representing the parts as they appear when 45 the platen is elevated.

Fig. 6 is an enlarged, detail, perspective view of one of the auxiliary feed rollers and the supporting rod therefor.

Fig. 7 is a detail, perspective view of one 50 of the detachable bars with a transfer sheet secured thereto.

Fig. 8 is a detail, transverse sectional view of the same.

Fig. 9 is a detail, diagrammatic, trans-

verse sectional view taken through the auxiliary work sheet support, the work sheet and slide.

Fig. 10 is a diagrammatic, fore and aft, vertical sectional view showing the parts as they appear when the work sheet and carbon 60 sheets are being positioned to start the work, and before a backward displacement of the carbon sheets has been effected.

Fig. 11 is a diagrammatic, vertical, fore and aft sectional view showing the disposition of the parts as they appear just after severing a previously written blank, or set of blanks, from the continuous work sheet.

I have shown my invention, in the present instance, embodied in a No. 10 Smith Premier machine in which the invention may be readily included at comparatively little expense and without materially modifying the structural features of the machine as they now exist. It should be understood, however, that the invention may be embodied in other styles of machines, and that certain features thereof may be used without others, or in other combinations. In the accompanying drawings only so much of the No. 70 75 80 10 Smith Premier machine is illustrated as may be necessary to arrive at an understanding of my invention in its embodiment therein.

The present construction while capable of 85 a wide range of uses is particularly adapted for use in connection with continuous work sheets of the "fan-fold" type in which a plurality of superposed webs or layers are 90 formed by folding the work sheet longitudinally so as to present alternately at opposite sides of the folded sheet openings between the layers in which interleaved transfer sheets are received.

By my invention I provide means by 95 which that portion of the continuous work sheet which ordinarily curves around the platen may be brought to a straight line position, or substantially to a straight line position, with another portion of the sheet 100 in the machine which is being fed to the platen. This is in order to facilitate a relative displacement between the transfer sheets and the work sheet. I have also provided hand actuated means which at this 105 time may be operated to effect a straight line backward displacement of the transfer sheet or sheets relatively to the work sheet.

Means are likewise provided for clamping the work sheet and holding it during the relative backward displacement of the transfer sheet for severing the written blanks 5 from the work sheet and for automatically positioning a previously written blank in proper position relatively to the clamp and cutter by the act of bringing a new blank to the printing line, all as will hereinafter 10 more clearly appear.

The frame of the machine comprises corner posts 1 and a top plate 2. Upwardly and rearwardly striking type bars 3 are mounted to impact against the front face of 15 a cylindrical rotative platen 4. The platen is mounted on a platen shaft 5 provided with finger wheels 6 which are secured to the ends thereof. The platen shaft is normally seated in bearings 7 in end plates 8 20 of the carriage. These end plates are secured by screws 9 to the base 10 of the carriage, which may constitute a paper table, and is provided with oppositely grooved bearings 11 in which anti-friction balls or 25 rollers 12 are received. These rollers are likewise received in oppositely grooved guides 13 in a fixed supporting or guide plate 14. The carriage is thus supported to travel from side to side of the machine over 30 the top plate, being propelled in its forward or letter space movement in the usual manner through gear wheels 15 which coact with a rack 16 carried by the carriage.

Any suitable main paper feed mechanism 35 may be employed. In the present instance the paper feed mechanism is similar to that disclosed in the patent to Alexander T. Brown, No. 1,023,808, dated April 23, 1912. Such mechanism comprises a floating paper 40 guide or apron 17 provided with a guiding member 18 which is substantially U-shaped in cross section and straddles a supporting bar or rod 19 carried by the carriage. A bowed leaf spring 20 is received in said 45 guide 18 and bears at its upper free ends against the bottom of the paper apron and at its central bowed portion against the supporting rod 19 to provide spring means for moving the floating paper apron and 50 the parts carried thereby toward the platen. A set of main paper feed rollers 21 are carried by the floating paper apron at the introductory side of the platen, and a set of feed rollers 22 are likewise carried by the paper 55 apron near the forward side of the platen and beneath the same. A platen scale plate 23 is secured to the paper apron and extends adjacent to the platen beneath the printing line. A release lever 24 is mounted on and 60 fixed to a pivot rod or rock shaft 25 which receives a pivotal support on the carriage. The upper end of the release lever is provided with a finger piece 26 by which it and the rock shaft may be actuated. The pivot 65 rod or rock shaft 25 carries fingers 27 which

project forwardly from the shaft and project over a flange 28 which extends rearwardly from the guide 18. A forward movement of the finger piece 26 is effective to turn the rock shaft 25 and force the paper apron down against the power of the spring 20, thus carrying the paper apron and feed rollers 21 and 22 away from the platen. The supporting bar 19 is connected at its ends to a frame, which comprises end members 29 70 pivoted at 30 to the carriage and detachably connected therewith, as indicated in the patent to Brown hereinbefore referred to. This frame also constitutes a support for the rock shaft 25 which carries the feed 75 roller release lever 24.

The right-hand end plate 8 of the carriage has a line spacing arm or lever 31 mounted thereon, said arm being effective to oscillate a carrier 32. This carrier supports a spring-pressed, sliding, line spacing pawl 33 which is adapted to coact with the teeth 34 of a line spacing wheel secured to the right-hand end of the platen. A spring 35 is effective to return the line spacing lever and the pawl 80 carrier to normal position. The line spacing mechanism referred to is similar to that disclosed in the patent to A. T. Brown, No. 887,584, dated May 12, 1908.

The parts, as thus far described, constitute a part of the equipment of the No. 10 Smith Premier machine and further detailed description thereof is deemed unnecessary.

I have provided an auxiliary work sheet 100 support which, in the present instance, extends rearwardly from the carriage and is connected to travel therewith and support the work sheet as it is led to the platen. Thus, supporting arms or side bars 36 are 105 secured by screws 37 to the base of the carriage and extend rearwardly therefrom and are substantially horizontally disposed where they project rearwardly from the upper end of the paper table formed by the 110 base of the carriage. These arms 36 are rigidly united by a sheet metal angle-bracket 38 which is secured thereto by screws 39. The depending flange 40 of this bracket carries midway in the length thereof an arm 41 115 secured to the flange by screws 42. A shouldered pivot screw 43 is received at its threaded end in a tapped opening in the arm 41 and constitutes a pivot for a roller 44. This roller is provided with a grooved periphery which rolls on a fixed track or support 45 which is formed as the cross bar of a three-sided frame, and unites the side members 46 of said frame. The parallel side arms 46 extend fore and aft of the 120 machine and are secured to the frame of the machine by screws 47. The arms 36 are likewise connected by a cross bar 48, which is preferably rounded on the upper side thereof, as indicated in Fig. 2, for purposes 125 130

which will hereinafter appear. This cross bar is adjustably connected to the side arms 36 by any suitable means such as thumb screws 49 which extend through openings 5 in the end portions of the cross bar and are received in tapped openings 50 in the side bars 36. It will be understood that by these means the cross bar 48 rigidly connects the side bars 36 and that the cross bar 48 is adjustable on the side arms or bars 36 to different positions fore and aft of the machine. A light sheet metal plate or support 51 is secured to the side bars 36 at the under sides of the same by headed screws 52. 10 From the foregoing description it will be understood that the plate 51, side arms 36, and cross bar 48 constitute an auxiliary paper table or support for the work sheet; that said support extends rearwardly from 15 the carriage and is supported by the roller 44 on the track 45 carried by the frame of the machine; and that this auxiliary paper table or support is adapted to travel with the carriage in the movement of the latter. 20 25 A slide or carrier, which is designated as a whole by the reference numeral 53, is mounted to move fore and aft of the machine on the auxiliary paper table and is supported by the latter and travels there- 30 with. This carrier or slide comprises a cross plate 54 which extends between the side bars 36 and is connected to angle plates 55 by screws 56. Each angle plate has a de- 35 pending flange 57 which extends outside of and parallel with the associated side bar 36. It will be understood therefore that the slide or carrier 53 is supported for move- 40 ment fore and aft of the machine on the auxiliary paper table and is guided in such movement by the depending flanges 57 of the angle plates 55. The slide is further guided by the ends of the cross plate 54, which are adjacent to the inner edges of the side bars 36. The construction is such there- 45 fore that the slide or carrier 53 is guided in its fore and aft movements on the auxiliary paper table or support (36-48-51) but may, if desired, be lifted off the latter. Each side of the slide 53 has fixedly secured 50 thereto a trough-like or substantially U-shaped member 58 which is open at its upper side and forms parallel side walls 59. Centrally disposed in each trough-like mem- 55 ber 58 is an upwardly projecting pin 60 which is secured at its lower end to the associate member 58. A wire guide 61 ex- 60 tends across the machine and is provided with depending ends 62 which are secured to the members 58. The cross bar of this 65 guide is thus maintained elevated above the auxiliary paper table, and the slide which carries it, and is intended to receive the work sheet which is inserted between the guide and the auxiliary paper table or work sheet support.

The carrier or slide 53 is intended as a carrier for an interleaved transfer sheet or sheets, and these sheets are connected to the carrier in the following manner:—

From an inspection of Fig. 7 it will be understood that each transfer or carbon sheet 63 is doubled at its rear end over a thin metal carrier or bar 64. This bar has a sheath 65 pivoted thereto at 66, so that the sheath and bar act as a jack-knife to bind the folded sheet between them and thus secure one end of the carbon sheet to the bar. Both the sheath and bar are made of sheet metal and occupy but little width-wise space. Each bar 64 is provided with an aperture 67 by which it may be mounted on one of the pins 60, the body portion of the bar being received in the associated trough-like member 58 so that the edges of the bar engage the inner parallel side walls 59 of said member 58 to prevent a turning or pivotal movement of each bar around its pin 60 when the bars are in place on the slide or carrier. From an inspection of Fig. 3 it will be understood that any suitable number of these bars may be arranged one above another on the pins 60 and that each bar projects from its point of support on the slide or carrier transversely of the machine, and is connected at one end only to the slide. These bars 64 with the transfer or carbon sheets attached thereto, may therefore be readily introduced into the folds of the work sheet and between the layers thereof and then connected to the slide. In Fig. 9 I have illustrated diagrammatically a work sheet, designated as a whole by the reference numeral 68, and which comprises in the example shown superposed layers or webs 69, 69^a, 69^b and 69^c. The work sheet is folded at its edges as indicated at 70, the openings between the webs alternating at opposite side edges of the work sheet. From this view it will be understood that the bars 64 are introduced between the layers at the openings and that the carbon or transfer sheets may be introduced with the bars and thus interleaved between the webs or layers of the work sheet, each bar projecting at its free end into a fold of the work sheet. In the example illustrated in Fig. 9 provision is made for writing an original 69 and three copies 69^a, 69^b and 69^c, the copies being produced through the interleaved transfer sheets.

The slide or carrier 53 remains indefinitely in the position to which it is moved on the work sheet support, there being sufficient friction between the slide and its support to retain it against accidental displacement from the position to which it is moved, but not enough friction to prevent the slide or carrier from being moved forward freely with the carbon sheets as the latter are fed

forwardly with the work sheet by the usual line spacing mechanism or paper feed devices, as will hereinafter more fully appear.

The work sheet as it is fed forward from 5 a suitable source of supply over the work sheet support or auxiliary table passes over the rounded side of the bar 48, along the plate 51, into the bight between the feed rollers and platen, around the platen and 10 up in front of the same past the printing line. The paper feed rollers co-act with the work sheet in the usual manner to feed it and the interleaved transfer sheets forward, the latter carrying forward the 15 slide 53.

In order that the work sheet may be brought to a substantially straight line position while it still remains in the machine, so as to facilitate a rearward displacement 20 of the carbon sheets with reference to the work sheet, I have provided means by which the platen may be separated from its co-operative paper feed devices and may be elevated to a position, such as that represented in Figs. 5 and 10, where the bottom 25 of the platen is at a height corresponding substantially to the plane of the auxiliary work sheet support. The means by which the platen is mounted so that it may be thus 30 shifted will now be described.

A platen frame is provided with bearing openings which receive the platen shaft 5. This platen frame comprises end bars 71 in which the bearing openings for the platen shaft are formed and which are united by a cross-bar 72 and are fixedly connected to the latter by pins 73. The cross bar 72 is carried by arms 74 to which the cross rod is fixedly connected by pins 75. The rear ends 35 of the arms 74 are mounted for pivotal movement in the rear of the platen on a supporting rod 76 which is fixed to the end plates 8 of the carriage. In this manner the platen frame is mounted to turn on a pivotal center in the rear of the platen around the axis of the supporting rod 76 and to move upwardly from the dotted line position represented in Fig. 5 to the full line position represented in that figure. It will be 40 understood that in the normal position of the parts, represented by dotted lines in Fig. 5, the platen shaft is supported in the bearings 7 of the carriage, and in a position where the platen co-acts with the paper 45 apron and feed rollers 21 and 22 to effect a forward feed of the work sheet in the usual manner. When, however, the platen is shifted from the dotted to the full line position, represented in Fig. 5, the platen is 50 separated from the paper feed devices 17, 21 and 22, and is moved to a position where the bottom of the platen is at a height which corresponds to, or substantially to, the plane of the auxiliary work sheet support in the 55 rear of the platen. At this time the work 60

sheet and interleaved carbon sheets at that portion thereof where it curves around the platen may be straightened out, or do straighten out, to a straight line position coincident, or substantially coincident, with 70 the plane of the work sheet supported on the work sheet support in the rear of the platen, as indicated in Fig. 10. It will be understood that when the parts are thus disposed the work sheet is freed from any binding 75 effect of the platen and that the interleaved carbon sheets may be readily displaced rearwardly relatively to the work sheet and while the latter is held against displacement from the position to which it has been moved. 80

In order to facilitate a relative displacement of the carbon sheets I have provided means for engaging and holding the work sheet which will now be described.

A frame, designated as a whole by the 85 reference numeral 77, is pivoted at opposite sides of the carriage to the platen frame, as indicated at 78. This auxiliary frame comprises side bars 79 which are pivoted directly to the platen frame at 78, and are 90 united by a cross bar or rod 80 fixed in bearings in the arm 79 by pins 81. The frame also comprises sheet metal arms 82 fixed to the cross bar 80 by screws 83. These arms terminate at 84 and are tapped to receive 95 the threaded ends of thumb screws 85 which are provided with shoulders 86. The shanks of these thumb screws extend through slots 87 in supporting arms 88 of a combined clamp and cutter. The shoulders 86 of the 100 thumb screws bear against the forward faces of the arms 88 and bind said arms against the arms 82 of the frame so as to maintain the arms 88 and the parts carried thereby in the position to which they may be adjusted 105 on the arms 82. The clamp which has been referred to, in the present instance, is in the nature of a two-part clamp comprising a sheet metal member 89, riveted at 90 to the supporting arms 88 and extending transversely across the machine throughout, or substantially throughout, the writing field. The upper end of this member 89 is bent rearwardly at 91 and may be provided with a knife-edge 92 for severing the written 110 blanks from the continuous work sheet. The other member of the clamp, in the present instance, comprises a member 93 which may be formed of sheet metal and has an engaging edge 94 which co-operates with the 115 rear face of the part 91 to clamp and hold the work sheet between said members. The lower or inner end of the member 93 is curved around and fixed to a longitudinally extending member 95 of a wire bail or yoke, 120 as indicated at 96, and as shown in Figs. 1 and 5. The bent ends 97 of the connecting bail are arranged outside of the clamping members 89 and 93 and connect with a longitudinally extending member 98 which is 125 130

received in a turned or bent portion 99 of the member 89. This provides a pivotal connection between said members and thus enables the member 93 to move from the 5 open position, represented in Fig. 2, to the closed or clamping position, represented in Fig. 5. By loosening the thumb screws 85 the clamp as a whole and the cutter 92 may be adjusted toward and away from the printing line, and may be secured in such adjusted position on the auxiliary frame by 10 tightening the thumb screws 85. The purpose of this adjustment is to accommodate the machine to blanks of different lengths as 15 will hereinafter more clearly appear. It will be understood that when the jaws of the clamp are open, as indicated in Fig. 1, the work sheet may pass freely between said jaws and may be clamped thereby when the 20 jaws are closed, as indicated in Fig. 11.

The cross rod 80, hereinbefore referred to, contains a spline groove 100 and constitutes a supporting rod which supports sheet metal bracket-like members or carriers, each designated as a whole by the reference numeral 101. Each of the carriers is mounted on the supporting rod 80 and is adapted to receive an adjustment along the same as well as a limited pivotal movement thereon. Each 25 member 101 carries an auxiliary or margin feed roller or device 102 which is adapted to co-act with the work sheet above the printing line, as indicated in Figs. 1 and 2, and to co-act with the platen to effect a forward 30 feed of the work sheet when the platen is rotated. Each carrier 101 is provided with a spline 103 which is received in the spline groove 100 but which, as may be understood from an inspection of Fig. 6, is smaller than 35 the width of the groove so as to afford a limited pivotal movement of each carrier 101 around the axis of the supporting rod 80. Coiled springs 104 surround the supporting rod, one of said springs being received between the arms of each carrier 101, and with 40 one of its ends engaging the carrier, as indicated at 105. The other end 106 of each spring is received in the spline groove 100, so as to anchor that end of each spring to 45 the supporting rod 80 and yet enable the associated carrier and the paper feed device or margin feed roller to be adjusted along the supporting rod. From an inspection of 50 Figs. 1, 2 and 4 it will be understood that 55 when the parts are in the normal position the paper feed devices or margin feed rollers bear with a spring pressure against the platen, or the work sheet thereon, above the printing line but that such pressure is released and the feed rollers 112 are moved 60 away from the platen when the frame 77 is moved to the position shown in Fig. 5.

I have provided means for locking or holding the auxiliary frame 77 against pivotal movement when it is in the normal or

substantially upright position, indicated in Figs. 1, 2 and 4, and in order to maintain the auxiliary paper feed devices 102 in cooperative relation with the platen or the work sheet thereon. This locking or holding means, in the present instance, is constructed as follows: A sheet metal bracket 107 is secured to the left-hand end plate of the carriage by a screw 108. This bracket extends forwardly and upwardly from the 75 carriage and is formed with an engaging edge 109 and with a flange 110 bent at right angles to the plane of the body portion of the bracket. The relation of the parts is such that when the platen is in the normal 80 position, the bearing portion for the rod 80 on the left-hand side bar 79 co-acts with the engaging portion 109 of the bracket arm, as indicated in dotted lines in Fig. 5, to prevent a pivotal movement of the auxiliary frame 85 77, and maintain the auxiliary paper feed rollers 102 against the platen. The relation of the parts is such that the left-hand supporting bar 79 of the auxiliary frame stands behind the flange 110 and in the upward 90 movement of the platen prevents a forward swinging movement of the auxiliary frame around its pivots 78 until the upper end of the flange 110 has been cleared. Thus a movement of the auxiliary frame from the 95 normal, or substantially upright position, to the substantially horizontally disposed position, represented in full lines in Fig. 5, may be effected. It will be understood that this forward pivotal movement of the auxiliary frame 77 is effective to carry the left-hand bar 79 over the upper end 111 of the flange 110, the two co-acting at this time to lock or maintain the platen in its elevated position, as indicated in full lines in Fig. 5. It will 100 be seen therefore that as long as the platen remains in its normal position the auxiliary frame 77, which carries the clamp, knife, and auxiliary feed rollers, will be held against pivotal movement on the platen 105 frame. It will be seen, moreover, that the frame 77 can only receive a pivotal movement from the upright position represented in Fig. 2 to the substantially horizontally 110 disposed position represented in full lines in Fig. 5, when the platen has been elevated to a position where the curved portion of the work sheet beneath the platen may be brought to a straight line position coincident with that portion of the work sheet which 115 is supported on the auxiliary work sheet support. From an inspection of Figs. 5 and 10 it will be understood that the pivotal center 78 on which the auxiliary frame 77 turns on the platen frame is located near the printing line and slightly below the same. It will be understood therefore that by reason of this fact the distance of the cutter and clamp from the printing line is the same or substantially the same when the parts are dis- 120 125 130

posed as represented in full lines in Fig. 5, as when the parts are disposed in the normal position represented in Fig. 2 for purposes which will presently appear.

5 It will be understood, moreover, that the bars 64 are arranged parallel with the axis of the platen and at a uniform distance therefrom. By reason of this fact the carbon or transfer sheets connected to said bars 10 may be of a uniform length and all terminate at the same point or line, as indicated diagrammatically in Figs. 10 and 11.

In employing my mechanism for use in connection with a continuous fan-fold work sheet the operation is as follows: It should be understood that the continuous work sheet is ordinarily printed with a series of blanks on each web; that these blanks are of a uniform size with, we will say, scored 15 or printed lines to indicate the lines of division between different bills or blanks on each web. While superposed blanks may differ somewhat in character the matter written on an outermost blank is copied 20 through the interposed transfer or carbon sheets on all of the other blanks of a set in a like manner. The outside blank or original, for example, may be a "freight bill", the next a "cashier's slip", the third a "check-out slip" and the fourth a "delivery receipt". 25 The scored or printed dividing lines between successive blanks on the first web are represented by the reference letter "a" in Fig. 1, so that the length of the blank on the outermost web in Fig. 1 is between two successive lines "a", and the companion forms on the other webs are of a corresponding length. The first writing line on each of these 30 blanks is indicated by the reference numeral 112, and the printing point or line is indicated by the reference numeral 113. Before 35 beginning the work the knife-blade or clamp is adjusted so that when the first writing line on one blank is at the printing line the top of the next blank toward the end of the sheet will be in register, or substantially in 40 register, with the engaging edge of the knife-blade or clamp, as indicated in Fig. 1. This adjustment having been effected the 45 continuous work sheet is taken from its source of supply over the upper curved face of the cross bar 48 and is threaded beneath the guide bar 61 and carried forward over the auxiliary support and over the platen, 50 while the parts are maintained in the positions indicated in Figs. 5 and 10. The forward end of the fan-fold sheet is brought substantially into register with the severing 55 blade or with the engaging portions of the clamp as represented in Fig. 10. The transfer sheets having been connected to the respective bars 64 they are introduced with the aid of the bars between the layers of the work sheet, as represented in Fig. 9, extending 60 alternately in opposite directions from

their points of support on the carrier or slide to which the bars are detachably connected. The transfer sheet should be adjusted relatively to the work sheet in the manner indicated in Fig. 10 with the forward 70 ends of the transfer sheets just in the rear of the forward end of the multiple work sheet, so that the forward or leading end of the work sheet may be engaged by the clamp, as indicated in Fig. 11, without engaging 75 the transfer sheets. When the transfer sheets have been interleaved between the layers of the work sheet in the manner indicated, and with the bars 64 secured on the pins 60 of the slide, the leading end of the 80 work sheet may be introduced beneath the platen and brought between the members of the clamp and engaged thereby at its forward free end while the platen is still maintained in the elevated position represented 85 in Fig. 10. The carrier or slide 53 may then be moved rearwardly from the full to the dotted line position represented in Fig. 10, or until the forward ends of the transfer sheets are just in the rear of the second set 90 of blanks on the work sheet, or just in the rear of the line "a" of severance between the first and second set of blanks. This extent of movement of the carrier or slide 53 having once been determined the cross bar 48 95 is adjusted on the side bars 36 to a position where it engages the slide and acts as a stop therefor in the subsequent backward movements of the slide. The openings 50 in the side bars, which provide for adjusting 100 the cross bar 48, are separated a suitable distance apart to enable the bar to be set for blanks of different lengths and to correspond substantially to the adjustment of the clamp and cutter-blade relatively to the 105 printing line. When the transfer sheets have been displaced rearwardly by the hand actuated slide 53 in the manner described, the platen will be lowered to its operative position indicated in Figs. 1, 2 and 4. The 110 second blank on the work sheet will then be in a position to receive the first line of writing, as indicated in Fig. 1. The operator proceeds to fill in the blank and the matter written will be copied on the other blanks 115 of the set. When this blank or set of blanks have been filled in the operator turns the platen to bring the first writing line 112 on the next blank to the printing line. This 120 positions the line of severance "a" between the first and second bills or blanks on the outermost web in register with the cutting blade or knife. The operator may then close the clamp and sever the first set of blanks, which in the beginning of the work are not 125 filled in and may be destroyed. Still maintaining the clamp closed so that it engages the work sheet at the forward end as represented in Fig. 11, but does not engage the forward ends of the interleaved transfer 130

sheets, the operator elevates the platen and turns the clamp to the substantially horizontally disposed position, shown in Fig. 5. The operator then moves the slide or carrier 5 from the forward position, represented in full lines in Fig. 10, to the dotted line position represented in that figure where it is arrested by the cross bar 48, the operator still maintaining the clamp closed on the 10 work sheet. The platen may again be lowered and the work sheet will be in a position to receive the first line of writing on the next outermost bill sheet, as represented in Fig. 1, and to be copied on the companion 15 blanks of the set through the interleaved transfer sheets. After the parts are once set work in this manner continues indefinitely, and no attention is required upon the part of the operator to properly position the work 20 sheet in the machine except that after the completion of each blank the operator brings the first writing line of the next succeeding blank opposite the printing line. Thus after one bill is written the operator turns 25 the platen to bring the next bill in position to receive the first line of writing. This automatically positions the work sheet so that a previously written blank, or set of blanks, may be properly severed at the di- 30 viding line with the aid of the knife. The work sheet is also properly positioned with reference to the clamp so that the latter may engage the work sheet without engaging the interleaved carbon sheets. The op- 35 erator then shifts the platen and while main- taining the work sheet engaged by the clamp moves the slide rearwardly by hand until said slide is arrested by the cross bar 48. The platen is then lowered and the operator 40 proceeds to write the next bill, feeding the slide forward as the carbon sheets are fed forward with the bill sheet, and so on the operations are repeated indefinitely.

From the foregoing description it will be 45 understood that the auxiliary frame which carries the clamp and cutter has the pivotal center on which it is adapted to turn on the platen frame so situated with reference to the printing line that in lowering the platen 50 and carrying the auxiliary frame to an up- right position with the work sheet the latter may roll on or around the surface of the platen without being displaced longitudinally with reference to the platen and the 55 printing line. It will also be understood that this auxiliary frame receives a shifting movement with the platen as the latter is shifted away from the paper apron but has a pivotal movement independent of its shift- 60 ing movement in order to carry the margin feed rollers away from the platen, and in order to lock the platen in its elevated position, etc. It will be observed, moreover, that the clamp and knife are mounted for bodily 65 movement with the work sheet and with

reference to the platen and that the platen is normally maintained by gravity in co-operative relation with the feed rollers 21 and 22 and the paper apron.

While I have described with considerable 70 detail the use of the mechanism in connection with a fan-fold work sheet it should be understood that the mechanism may be used in other classes of work where it may be found available and that various changes 75 may be made without departing from the scope of my invention.

What I claim as new and desire to secure by Letters Patent, is:

1. In a typewriting machine, the combina- 80 tion of a carriage, a rotative platen carried thereby, feed rollers which co-act with said platen to feed forward a longitudinally folded work sheet and interleaved transfer sheets, and superposed bars parallel with the 85 axis of the platen and which extend into folds of the work sheet and to which the interleaved transfer sheets are attached, said bars being fed forward with the work sheet and the transfer sheets, the bars being a uni- 90 form distance from the axis of the platen so that transfer sheets of a uniform length attached to said bars will all terminate at a single point.

2. In a typewriting machine, the combina- 95 tion of a carriage, a rotative platen carried thereby, feed rollers which co-act with said platen to feed forward a longitudinally folded work sheet and interleaved transfer sheets, superposed bars parallel with the axis 100 of the platen and which extend into folds of the work sheet and to which the interleaved transfer sheets are attached, said bars being fed forward with the work sheet and the transfer sheets, and a single connecting de- 105 vice by which a plurality of said bars may be detachably connected to the member which directly supports them.

3. In a typewriting machine, the combina- 110 tion of a carriage, a rotative platen carried thereby, feed rollers which co-act with said platen to feed forward a longitudinally folded work sheet and interleaved transfer sheets, superposed bars parallel with the axis 115 of the platen and which extend into folds of the work sheet and to which the interleaved transfer sheets are attached, said bars being fed forward with the work sheet and the transfer sheets, a slide, and pins fixed to and projecting from said slide and adapted to 120 be received in apertures in said bars to detachably support the bars one on top of another.

4. In a typewriting machine, the combina- 125 tion of a platen, bars arranged one on top of another and extending into the folds of a folded work sheet as the latter extends to the platen and to which bars interleaved transfer sheets are attached, and pins on which said bars are detachably mounted, a 130

plurality of bars being adapted to be received on each pin.

5. In a typewriting machine, the combination of a platen, bars arranged one on top of another and extending into the folds of a folded work sheet as the latter extends to the platen and to which bars interleaved transfer sheets are attached, a movable carrier on which said bars are mounted, and 10 pins fixed to said carrier and on each of which a plurality of said bars is adapted to be detachably supported.

6. In a typewriting machine, the combination of a platen, a bar having a perforation 15 therein and extending into a fold of a folded work sheet as the latter extends to the platen, a carrier on which said bar is mounted and in which a trough-like pocket is formed and in which pocket the bar is adapted to be seated, and a pin in said pocket and which is adapted to extend through the perforation in the bar to detachably hold the bar on the carrier.

7. In a typewriting machine, the combination of a rotative platen, a paper apron beneath the platen, a paper table in the rear of the platen, and means which enable the platen to be elevated independently of the paper apron to a point where the bottom of 30 the platen is approximately as high as the upper end of the paper table, said means comprising a frame which supports the platen and is pivoted in the rear thereof and remote from the surface of the platen, so 35 that the platen may swing up and down around the pivotal center of said frame in the rear of the platen.

8. In a typewriting machine, the combination of a platen shaft; a platen mounted 40 thereon; finger wheels on said shaft; means for supporting a work sheet substantially in a flat condition in the rear of the platen; means for guiding the work sheet around and beneath said platen to the front thereof; 45 and means for mounting the platen so as to enable it to be shifted relatively to said guiding means and to an extent which will enable the work sheet beneath the platen to be brought substantially into a flat condition and to a plane substantially coincident with the plane of the flat portion of the work sheet on said supporting means, said mounting means comprising a frame in which the platen shaft is mounted to turn and which is 50 pivoted in the rear of the platen and remote from the surface of the platen, the platen swinging in an arc around the pivotal center of said frame in the rear of the platen.

9. In a typewriting machine, the combination of a platen shaft; a platen mounted 60 thereon; finger wheels on said shaft; means for supporting a work sheet substantially in a flat condition in the rear of the platen; means for guiding the work sheet around and beneath said platen to the front thereof;

means for mounting the platen so as to enable it to be shifted relatively to said guiding means and to an extent which will enable the work sheet beneath the platen to be brought substantially into a flat condition 70 and to a plane substantially coincident with the plane of the flat portion of the work sheet on said supporting means, said mounting means comprising a frame in which the platen shaft is mounted to turn and which is 75 pivoted in the rear of the platen, the platen swinging in an arc around the pivotal center of said frame in the rear of the platen; a line spacing wheel carried by the platen; and a line spacing pawl co-operative with 80 said line spacing wheel and relatively to which said wheel is shifted when the platen is moved away from said guiding means.

10. In a typewriting machine, the combination of a rotative platen, means for supporting a work sheet substantially in a flat condition in the rear of the platen, means for guiding the work sheet around beneath the platen and to the front thereof, means for mounting the platen so as to enable it 90 to be shifted relatively to said guiding means and to an extent which will enable the work sheet beneath the platen to be brought substantially into a flat condition and to a plane substantially coincident with the 95 plane of the flat portion of the work sheet on said supporting means, feed rollers which co-act with the platen above the printing line, and means which enable the feed rollers to be moved away from the platen when the 100 latter has been shifted away from said guiding means.

11. In a typewriting machine, the combination of a rotative platen, means for supporting a work sheet substantially in a flat 105 condition in the rear of the platen, means for guiding the work sheet around beneath the platen and to the front thereof, means for mounting the platen so as to enable it to be shifted relatively to said guiding means 110 and to an extent which will enable the work sheet beneath the platen to be brought substantially into a flat condition and to a plane substantially coincident with the plane of the flat portion of the work sheet on said 115 supporting means, feed rollers which co-act with the platen above the printing line, and means whereby said feed rollers are locked in operative position when the platen is in the normal position and by which they are 120 released from their locking means when the platen is shifted away from said guiding means.

12. In a typewriting machine, the combination of a rotative platen, means for 125 supporting a work sheet substantially in a flat condition in the rear of the platen, means for guiding the work sheet around beneath the platen and to the front thereof, means for mounting the platen so as to en- 130

able it to be shifted relatively to said guiding means and to an extent which will enable the work sheet beneath the platen to be brought substantially into a flat condition 5 and to a plane substantially coincident with the plane of the flat portion of the work sheet on said supporting means, feed rollers which co-act with the platen above the printing line, a pivoted frame which carries said feed rollers, and means for locking said frame against pivotal movement with the feed rollers against the platen when the platen is in the normal position and for releasing said frame for pivotal movement 10 when the platen is shifted away from said guiding means.

13. In a typewriting machine, the combination of a rotative platen, means for supporting a work sheet substantially in a flat condition in the rear of the platen, means for guiding the work sheet around beneath the platen and to the front thereof, means for mounting the platen so as to enable it to be shifted relatively to said guiding means 20 and to an extent which will enable the work sheet beneath the platen to be brought substantially into a flat condition and to a plane substantially coincident with the plane of the flat portion of the work sheet on said supporting means, feed rollers which co-act with the platen above the printing line, a pivoted frame which carries said feed rollers, and a work sheet clamp carried by 25 said frame.

14. In a typewriting machine, the combination of a rotative platen, means for supporting a work sheet substantially in a flat condition in the rear of the platen, means for guiding the work sheet around beneath the platen and to the front thereof, means for mounting the platen so as to enable it to be shifted relatively to said guiding means and to an extent which will enable the work 30 sheet beneath the platen to be brought substantially into a flat condition and to a plane substantially coincident with the plane of the flat portion of the work sheet on said supporting means, feed rollers which co-act with the platen above the printing line, a pivoted frame which carries said feed rollers, and a work sheet severing knife carried by 35 said frame.

15. In a typewriting machine, the combination of a rotative platen, means for supporting a work sheet substantially in a flat condition in the rear of the platen, means for guiding the work sheet around beneath the platen and to the front thereof, means for mounting the platen so as to enable it to be shifted relatively to said guiding means 40 and to an extent which will enable the work sheet beneath the platen to be brought substantially into a flat condition and to a plane substantially coincident with the plane of the flat portion of the work sheet on 45

said supporting means, feed rollers which co-act with the platen above the printing line, a pivoted frame which carries said feed rollers, and a work sheet clamp carried by said frame, one member of said clamp 70 constituting a knife for severing the work sheet.

16. In a typewriting machine, the combination of a rotative platen, a guide for guiding a work sheet around the platen, 75 means for mounting said platen so that it may be shifted away from said paper guide, feed rollers which co-act with the platen, and a frame which carries said feed rollers, said frame shifting with the platen as the 80 latter moves away from said paper guide and having a movement independent of its shifting movement to carry the feed rollers away from the platen.

17. In a typewriting machine, the combination of a rotative platen, a guide for guiding a work sheet around the platen, means for mounting said platen so that it may be shifted away from said paper guide, a frame 85 which shifts with the platen in the movement of the latter toward and away from said paper guide and which also has a movement independently of said shifting movement, and a work sheet clamp carried by 90 said frame.

18. In a typewriting machine, the combination of a rotative platen, a guide for guiding a work sheet around the platen, means for mounting said platen so that it may be shifted away from said paper guide, a frame 100 which shifts with the platen in the movement of the latter toward and away from said paper guide and which also has a movement independently of said shifting movement, and a work sheet clamp carried by 105 said frame, said work sheet clamp comprising two members between which the work sheet passes and which may be closed at will against the work sheet.

19. In a typewriting machine, the combination of a rotative platen, a guide for guiding a work sheet around the platen, means for mounting said platen so that it may be shifted away from said paper guide, a frame 110 which shifts with the platen in the movement of the latter toward and away from said paper guide and which also has a movement independently of said shifting movement, and a work sheet severing knife carried by 115 said frame and having a bodily movement therewith during said independent movement of the frame.

20. In a typewriting machine, the combination of a rotative platen, a guide for guiding a work sheet around the platen, means 125 for mounting said platen so that it may be shifted away from said paper guide, a frame which shifts with the platen in the movement of the latter toward and away from said paper guide and which also has a move- 130

ment independently of said shifting movement, and a work sheet clamp carried by said frame, said work sheet clamp comprising two members between which the work sheet passes and which may be closed at will against the work sheet, one of said members constituting a work sheet severing knife.

21. In a typewriting machine, the combination of a rotative platen, a guide for guiding a work sheet around the platen, means for mounting said platen so that it may be shifted away from said paper guide, a frame which shifts with the platen in the movement of the latter toward and away from said paper guide and which also has a movement independently of said shifting movement, said frame normally having substantially an upright position and being movable by its independent movement to substantially a horizontal position, and means which co-act with said frame to hold the platen elevated and away from the paper guide when the frame is in the substantially horizontal position.

25 22. In a typewriting machine, the combination of a rotative platen, a guide for guiding a work sheet around the platen, means for mounting said platen so that it may be shifted away from said paper guide,

30 a frame which shifts with the platen in the movement of the latter toward and away from said paper guide and which also has a movement independently of said shifting movement, said frame normally having sub-

35 stantially an upright position and being movable by its independent movement to substantially a horizontal position, and retaining means which prevent said frame from moving to the horizontal position when

40 the platen is in its normal position but which releases the frame and enables it to be moved to the horizontal position when the platen is elevated away from the paper guide, said frame when horizontally disposed co-acting

45 with said retaining means to hold the platen in the elevated position.

23. In a typewriting machine, the combination of a rotative platen, a guide for guiding a work sheet around the platen, means
50 for mounting said platen so that it may be shifted away from said paper guide, a frame which shifts with the platen in the movement of the latter toward and away from said paper guide and which also has a movement
55 independently of said shifting movement, said frame normally having substantially an upright position and being movable by its independent movement to substantially a horizontal position, retaining
60 means which prevent said frame from moving to the horizontal position when the platen is in its normal position but which releases the frame and enables it to be moved to the horizontal position when the platen is
65 elevated away from the paper guide, said

frame when horizontally disposed co-acting with said retaining means to hold the platen in the elevated position, and a work sheet clamp carried by said frame.

24. In a typewriting machine, the combination of a rotative platen, a guide for guiding a work sheet around the platen, means for mounting said platen so that it may be shifted away from said paper guide, a frame which shifts with the platen in the movement of the latter toward and away from said paper guide and which also has a movement independently of said shifting movement, said frame normally having substantially an upright position and being movable by its independent movement to substantially a horizontal position, retaining means which prevent said frame from moving to the horizontal position when the platen is in its normal position but which releases the frame and enables it to be moved to the horizontal position when the platen is elevated away from the paper guide, said frame when horizontally disposed co-acting with said retaining means to hold the platen in the elevated position, and a work sheet clamp carried by said frame, one member of said clamp constituting a knife for severing the work sheet. 70 75 80 85 90

25. In a typwriting machine, the combination of a rotative platen, a guide for guiding a work sheet around the platen, means for mounting said platen so that it may be shifted away from said paper guide, a frame which shifts with the platen in the movement of the latter toward and away from said paper guide and which also has a movement independently of said shifting movement, said frame normally having substantially an upright position and being movable by its independent movement to substantially a horizontal position, retaining means which prevent said frame from moving to the horizontal position when the platen is in its normal position but which releases the frame and enables it to be moved to the horizontal position when the platen is elevated away from the paper guide, said frame when horizontally disposed co-acting with said retaining means to hold the platen in the elevated position, a work sheet clamp carried by said frame, and means for affording an adjustment of said clamp with reference to the printing line. 115

26. In a typewriting machine, the combination of a rotative platen, a guide for guiding a work sheet around the platen, means for mounting said platen so that it may be shifted away from said paper guide, a frame which shifts with the platen in the movement of the latter toward and away from said paper guide and which also has a movement independently of said shifting movement, said frame normally having substantially an upright position and being 130

movable by its independent movement to substantially a horizontal position, retaining means which prevent said frame from moving to the horizontal position when the 5 platen is in its normal position but which releases the frame and enables it to be moved to the horizontal position when the platen is elevated away from the paper guide, said frame when horizontally disposed co-acting 10 with said retaining means to hold the platen in the elevated position, a knife carried by said frame for severing the work sheet, and means for affording an adjustment of said knife relatively to the printing line.

15 27. In a typewriting machine, the combination of a carriage, a platen, means for supporting a series of webs of printed blanks with interleaved carbon sheets and for feeding the same together past the printing line, 20 a knife which is located at a distance beyond the printing line greater than the length of a blank on the webs, and means for simultaneously shifting the carbon sheets back relatively to the webs whereby a previously 25 written batch of superposed blanks may be severed from the webs without first withdrawing the carbon sheets backwardly relatively to the webs and without cutting the carbon sheets.

30 28. In a typewriting machine, the combination of a platen, a knife for severing printed blanks from a continuous work sheet, said knife being situated with reference to the printing line at a distance that corresponds 35 to the distance from the top of one blank to the first writing line on the next succeeding blank, and means for affording an adjustment of said knife toward and away from the printing line to accommodate the knife 40 to blanks of different lengths.

29. In a typewriting machine, the combination of a platen, a knife for severing printed blanks from a continuous work sheet, said knife being situated with reference to the 45 printing line at a distance that corresponds to the distance from the top of one blank to the first writing line on the next succeeding blank, and a pivoted frame on which said knife is mounted, the pivotal center of said 50 frame being near the printing line so that the knife will be at or substantially at the same distance from the printing line in the different positions to which the frame may be moved.

55 30. In a typewriting machine, the combination of a platen, and a knife for severing a continuous work sheet, said knife being movable into and out of engagement with the work sheet and being mounted for an independent bodily pivotal movement with the work sheet and with reference to the platen, the pivotal center of the knife in said bodily movement being near the printing line.

31. In a typewriting machine, the combination of a platen, a knife for severing a

continuous work sheet, said knife being mounted for bodily pivotal movement with the work sheet and with reference to the platen, the pivotal center of the knife in said bodily movement being near the printing 70 line, and means for adjusting said knife with reference to the printing line to different set positions.

32. In a typewriting machine, the combination of a platen, and a work sheet clamp 75 mounted for bodily pivotal movement with reference to the platen and around a pivotal center near the printing line.

33. In a typewriting machine, the combination of a platen, a work sheet clamp 80 mounted for bodily pivotal movement with reference to the platen and around a pivotal center near the printing line, and means for affording a bodily adjustment of said clamp to different set positions with reference to 85 said pivotal center.

34. In a typewriting machine, the combination of a platen, and a work sheet clamp 90 mounted for bodily pivotal movement with reference to the platen and around a pivotal center near the printing line, said clamp comprising two members between which the work sheet is adapted to be received and one of said members constituting a blade by which the work sheet may be severed. 95

35. In a typewriting machine, the combination of a platen; a work sheet clamp mounted for bodily pivotal movement with reference to the platen and around a pivotal center near the printing line, said clamp comprising two members between which the work sheet is adapted to be received and one of said members constituting a blade by which the work sheet may be severed, the members of said clamp being normally open 100 and adapted to be closed at will on the work sheet; and means which afford a bodily adjustment of the clamp to different set positions relatively to said pivotal center. 105

36. In a typewriting machine, the combination of a platen, a knife for severing printed blanks from a continuous work sheet, said knife being so situated with reference to the printing line that when the line of severance between two blanks is in register with said 110 knife the first line to be written on a blank will be at the printing line, a pivoted frame on which said knife is mounted, and paper feed rollers carried by said frame and co-operative with the platen or the work sheet 115

thereon. 37. In a typewriting machine, the combination of a platen, a knife for severing printed blanks from a continuous work sheet, said knife being so situated with reference to the printing line that when the line of severance between two blanks is in register with said knife the first line to be 125 written on a blank will be at the printing line, a pivoted frame on which said knife 130

is mounted, paper feed rollers carried by said frame and coöperative with the platen or the work sheet thereon, and means for affording an adjustment of said knife toward and away from the printing line to different set positions and independently of said feed rollers.

38. In a typewriting machine, the combination of a platen, a work sheet clamp 10 adapted to engage a continuous work sheet along a line which divides two printed blanks thereon and so situated with reference to the printing line that when the work sheet is thus engaged the first line to be 15 written on a blank will be at the printing line, and means for affording an adjustment of said clamp to different set positions relatively to the printing line.

39. In a typewriting machine, the combination of a platen, a work sheet clamp 20 adapted to engage a continuous work sheet along a line which divides two printed blanks thereon and so situated with reference to the printing line that when the work sheet is thus engaged the first line to be 25 written on a blank will be at the printing line, and a pivoted frame which carries said clamp, the pivotal center of said frame being near the printing line.

30 40. In a typewriting machine, the combination of a platen, a work sheet clamp adapted to engage a continuous work sheet along a line which divides two printed blanks thereon and so situated with reference to the printing line that when the work sheet is thus engaged the first line to be 35 written on a blank will be at the printing line, a pivoted frame which carries said clamp, the pivotal center of said frame being near 40 the printing line, and paper feed rollers carried by said frame and coöperative with the platen or the work sheet thereon.

41. In a typewriting machine, the combination of a platen, a work sheet clamp 45 adapted to engage a continuous work sheet along a line which divides two printed blanks thereon and so situated with reference to the printing line that when the work sheet is thus engaged the first line to be 50 written on a blank will be at the printing line, a pivoted frame which carries said clamp, the pivotal center of said frame being near the printing line, paper feed rollers carried by said frame and coöperative with the platen or the work sheet thereon, and means for affording an adjustment of said 55 clamp to different set positions relatively to the printing line and independently of said feed rollers.

60 42. In a typewriting machine, the combination of a platen, paper feed rollers coöperative therewith, means for effecting a separation between the platen and said feed rollers, a work sheet clamp adapted to 65 engage a continuous work sheet along a line

which divides two printed blanks thereon and so situated with reference to the printing line that when the work sheet is thus engaged the first line to be written on a blank will be at the printing line, a pivoted 70 frame which carries said clamp, and means for normally holding said frame against pivotal movement and for freeing the frame to receive pivotal movement when the platen and feed rollers are separated.

43. In a typewriting machine, the combination of a platen, paper feed rollers coöperative therewith, means for effecting a separation between the platen and said feed rollers, a work sheet clamp adapted to engage a continuous work sheet along a line which divides two printed blanks thereon and so situated with reference to the printing line that when the work sheet is thus engaged the first line to be written on a 80 blank will be at the printing line, a pivoted frame which carries said clamp, means for normally holding said frame against pivotal movement and for freeing the frame to receive pivotal movement when the platen and feed rollers are separated, and auxiliary feed rollers coöperative with the platen and carried by said pivoted frame.

44. In a typewriting machine, the combination of a platen, paper feed rollers coöperative therewith, means for effecting a separation between the platen and said feed rollers, a work sheet clamp adapted to engage a continuous work sheet along a line which divides two printed blanks thereon 100 and so situated with reference to the printing line that when the work sheet is thus engaged the first line to be written on a blank will be at the printing line, a pivoted frame which carries said clamp, means for normally holding said frame against pivotal movement and for freeing the frame to receive pivotal movement when the platen and feed rollers are separated, and auxiliary feed rollers coöperative with the platen and carried by said pivoted frame.

45. In a typewriting machine, the combination of a platen, paper feed rollers coöperative therewith, means for effecting a separation between the platen and said feed rollers, a work sheet clamp adapted to engage a continuous work sheet along a line 110 which divides two printed blanks thereon and so situated with reference to the printing line that when the work sheet is thus engaged the first line to be written on a blank will be at the printing line, one member of said clamp being in the nature of a knife blade by which the work sheet may be severed, so that the clamp is operative as a clamp and also as a knife, a pivoted frame 120 which carries said clamp, the pivotal center 125

of said frame being near the printing line, auxiliary feed rollers carried by said frame and co-operative with the platen, and means which normally holds said frame against 5 pivotal movement but permits a pivotal movement thereof to be effected when the platen and feed rollers are separated.

46. In a typewriting machine, the combination of a carriage, a rotative platen carried thereby, feed rollers which co-operate with the platen to feed forward a work sheet or sheets and an interleaved transfer sheet, a carrier to which the transfer sheet is attached and by which it may be moved backward 10 independently of the work sheet or sheets, and a clamp-operative at will to engage only the work sheet or sheets and hold the same while the backward movement of the transfer sheet is being effected.

20 47. In a typewriting machine, the combination of a carriage, a rotative platen carried thereby, feed rollers which co-operate with the platen to feed forward a work sheet or sheets and an interleaved transfer sheet, 25 a carrier to which the transfer sheet is attached and by which it may be moved backward independently of the work sheet or sheets, and a clamp operative at will to engage only the work sheet or sheets and hold 30 the same while the backward movement of the transfer sheet is being effected, the distance from the point of engagement of the clamp to the printing line corresponding to the distance between the leading end of one 35 blank on a work sheet and the first writing line on another blank.

48. In a typewriting machine, the combination of a carriage, a rotative platen carried thereby, feed rollers which co-operate 40 with the platen to feed forward a work sheet or sheets and an interleaved transfer sheet, a carrier to which the transfer sheet is attached and by which it may be moved backward independently of the work sheet or 45 sheets, a clamp operative at will to engage only the work sheet or sheets and hold the same while the backward movement of the transfer sheet is being effected, the distance from the point of engagement of the clamp 50 to the printing line corresponding to the distance between the leading end of one blank on a work sheet and the first writing line on another blank, and means for affording 55 an adjustment of said clamp relatively to the printing line.

49. In a typewriting machine, the combination of a carriage, a rotative platen carried thereby, feed rollers which co-operate with the platen to feed forward a work sheet 60 or sheets and an interleaved transfer sheet, a carrier to which the transfer sheet is attached and by which it may be moved backward independently of the work sheet or sheets, a clamp operative at will to engage 65 only the work sheet or sheets and hold the

same while the backward movement of the transfer sheet is being effected, the distance from the point of engagement of the clamp to the printing line corresponding to the distance between the leading end of one blank 70 on a work sheet and the first writing line on another blank, means for affording an adjustment of said clamp relatively to the printing line, and adjustable means for limiting the movement of the carrier for the 75 transfer sheet in one direction.

50. In a typewriting machine, the combination of a carriage, a rotative platen carried thereby, feed rollers which co-act with said platen to feed forward a longitudinally 80 folded work sheet with an interleaved transfer sheet, a bar which is received in a fold of the work sheet and to which the transfer sheet is attached, a carrier to which one end only of said bar is affixed, said carrier 85 being moved in one direction by the feed of the transfer sheet and being moved in the opposite direction by and adapted to remain indefinitely in any position to which it is moved, and a clamp operative at will to 90 engage the work sheet and hold the same while the transfer sheet is being moved backward by the carrier.

51. In a typewriting machine, the combination of a carriage, a rotative platen carried thereby, feed rollers which co-act with said platen to feed forward a longitudinally 95 folded work sheet with an interleaved transfer sheet, a bar which is received in a fold of the work sheet and to which the transfer 100 sheet is attached, a carrier to which one end only of said bar is affixed, said carrier being moved in one direction by the feed of the transfer sheet and being moved in the opposite direction by hand and adapted to remain indefinitely in any position to which it is moved, and a clamp operative at will to 105 engage the work sheet and hold the same while the transfer sheet is being moved backward by the carrier, the distance from the 110 point of engagement of the clamp to the printing line corresponding to the distance between the leading end of one blank on a work sheet and the first writing line on another blank.

52. In a typewriting machine, the combination of a carriage, a rotative platen carried thereby, feed rollers which co-act with said platen to feed forward a longitudinally 115 folded work sheet with an interleaved transfer sheet, a bar which is received in a fold of the work sheet and to which the transfer sheet is attached, a carrier to which one end only of said bar is affixed, said carrier being moved in one direction by the feed of the transfer sheet and being moved in the opposite direction by hand and adapted to remain indefinitely in any position to which it is moved, and a clamp operative at will to 120 engage the work sheet and hold the same while 125 the transfer sheet is being moved in the opposite direction by hand and adapted to remain indefinitely in any position to which it is moved, and a clamp operative at will to engage the work sheet and hold the same while 130

the transfer sheet is being moved backward by the carrier, one member of said clamp constituting a blade by which the work sheet may be severed.

5. 53. In a typewriting machine, the combination of a carriage, a rotative platen carried thereby, means for supporting a longitudinally folded work sheet in substantially a flat condition in the rear of the platen, 10 means for guiding the work sheet around beneath the platen and to the front thereof, means for mounting the platen so as to enable it to be shifted relatively to said guiding means and to an extent which will enable 15 the work sheet beneath the platen to be brought substantially into a flat condition and to a plane substantially coincident with the plane of the flat portion of the work sheet on said supporting means, feed rollers 20 which co-act with the platen to feed forward the folded work sheet with an interleaved transfer sheet, a bar which is received in a fold in the work sheet and to which the transfer sheet is attached, a carrier to which 25 one end only of said bar is attached, said carrier being moved in one direction by the feed of the transfer sheet and being moved in the opposite direction by hand and adapted to remain indefinitely in any position to 30 which it is moved, and a clamp operative at will to engage the work sheet and hold it while the transfer sheet is moved backward by said carrier.

54. In a typewriting machine, the combination of a carriage, a rotative platen carried thereby, means for supporting a longitudinally folded work sheet in substantially a flat condition in the rear of the platen, means for guiding the work sheet around beneath the platen and to the front thereof, 35 means for mounting the platen so as to enable it to be shifted relatively to said guiding means and to an extent which will enable the work sheet beneath the platen to be brought substantially into a flat condition and to a plane substantially coincident with the plane of the flat portion of the work sheet on said supporting means, feed rollers 40 which co-act with the platen to feed forward the folded work sheet with an interleaved transfer sheet, a bar which is received in a fold in the work sheet and to which the transfer sheet is attached, a carrier to which 45 one end only of said bar is attached, said carrier being moved in one direction by the feed of the transfer sheet and being moved in the opposite direction by hand and adapted to remain indefinitely in any position to 50 which it is moved, and a clamp operative at will to engage the work sheet and hold it while the transfer sheet is moved backward by said carrier, the distance from the point of engagement of the clamp to the printing line corresponding to the distance between 55

the end of one blank on a work sheet and 65 the first writing line on another blank.

55. In a typewriting machine, the combination of a carriage, a rotative platen carried thereby, means for supporting a longitudinally folded work sheet in substantially 70 a flat condition in the rear of the platen, means for guiding the work sheet around beneath the platen and to the front thereof, means for mounting the platen so as to enable it to be shifted relatively to said guiding means and to an extent which will enable 75 the work sheet beneath the platen to be brought substantially into a flat condition and to a plane substantially coincident with the plane of the flat portion of the work sheet on said supporting means, feed rollers 80 which co-act with the platen to feed forward the folded work sheet with an interleaved transfer sheet, a bar which is received in a fold in the work sheet and to which the transfer sheet is attached, a carrier to which 85 one end only of said bar is attached, said carrier being moved in one direction by the feed of the transfer sheet and being moved in the opposite direction by hand and adapted 90 to remain indefinitely in any position to which it is moved, a clamp operative at will to engage the work sheet and hold it while the transfer sheet is moved backward by said carrier, the distance from the point of engagement of the clamp to the printing line corresponding to the distance between the leading end of one blank on a work sheet and the first writing line on another blank, 95 means for affording an adjustment of said clamp relatively to the printing line, and adjustable means for limiting the movement of said carrier in one direction.

56. In a typewriting machine, the combination of a carriage, a rotative platen carried thereby, means for supporting a longitudinally folded work sheet in substantially 105 a flat condition in the rear of the platen, means for guiding the work sheet around beneath the platen and to the front thereof, 110 means for mounting the platen so as to enable it to be shifted relatively to said guiding means and to an extent which will enable the work sheet beneath the platen to be brought substantially into a flat condition 115 and to a plane substantially coincident with the plane of the flat portion of the work sheet on said supporting means, feed rollers which co-act with the platen to feed forward 120 the folded work sheet with an interleaved transfer sheet, a bar which is received in a fold in the work sheet and to which the transfer sheet is attached, a carrier to which 125 one end only of said bar is attached, said carrier being moved in one direction by the feed of the transfer sheet and being moved in the opposite direction by hand and adapted to remain indefinitely in any position to

which it is moved, a clamp operative at will to engage the work sheet and hold it while the transfer sheet is moved backward by said carrier, the distance from the point of engagement of the clamp to the printing line corresponding to the distance between the leading end of one blank on a work sheet and the first writing line on another blank, and a pivoted frame which carries said clamp, the pivotal center of said frame being near the printing line.

57. In a typewriting machine, the combination of a carriage, a rotative platen carried thereby, means for supporting a longitudinally folded work sheet in substantially a flat condition in the rear of the platen, means for guiding the work sheet around beneath the platen and to the front thereof, means for mounting the platen so as to enable it to be shifted relatively to said guiding means and to an extent which will enable the work sheet beneath the platen to be brought substantially into a flat condition and to a plane substantially coincident with the plane of the flat portion of the work sheet on said supporting means, feed rollers which co-act with the platen to feed forward the folded work sheet with an interleaved transfer sheet, a bar which is received in a fold in the work sheet and to which the transfer sheet is attached, a carrier to which one end only of said bar is attached, said carrier being moved in one direction by the feed of the transfer sheet and being moved in the opposite direction by hand and adapted to remain indefinitely in any position to which it is moved, a clamp operative at will to engage the work sheet and hold it while the transfer sheet is moved backward by said carrier, the distance from the point of engagement of the clamp to the printing line corresponding to the distance between the end of one blank on a work sheet and the first writing line on another blank, a pivoted frame which carries said clamp, the pivotal center of said frame being near the printing line, and means which normally hold the pivoted frame against pivotal movement but enable such pivotal movement to be effected when the platen is shifted away from said guiding means.

58. In a typewriting machine, the combination of a carriage, a rotative platen carried thereby, feed rollers which co-act with said platen to feed forward a longitudinally folded work sheet with an interleaved transfer sheet, a bar which is received in a fold of the work sheet and to which the transfer sheet is attached, a carrier to which one end only of said bar is affixed, said carrier being moved in one direction by the feed of the transfer sheet and being moved in the opposite direction by hand and adapted to remain indefinitely in any position to which it

is moved, a clamp operative at will to engage the work sheet and hold the same while the transfer sheet is being moved backward by the carrier, a pivoted frame which carries said clamp, and means co-operative with said frame to hold the platen separated from said guiding means.

59. In a typewriting machine, the combination of a carriage, a rotative platen carried thereby, feed rollers which co-act with said platen to feed forward a longitudinally folded work sheet with an interleaved transfer sheet, a bar which is received in a fold of the work sheet and to which the transfer sheet is attached, a carrier to which one end only of said bar is affixed, said carrier being moved in one direction by the feed of the transfer sheet and being moved in the opposite direction by hand and adapted to remain indefinitely in any position to which it is moved, a clamp operative at will to engage the work sheet and hold the same while the transfer sheet is being moved backward by the carrier, feed rollers which co-act with the platen, a pivoted frame which carries said clamp and feed rollers, and means which normally hold the pivoted frame against pivotal movement but enable such pivotal movement to be effected when the platen is shifted away from said guiding means and with which the frame co-acts to hold the platen separated from said guiding means.

60. In a typewriting machine, the combination of a carriage, a rotative platen carried thereby, means for directing a work sheet substantially in a flat condition to the platen and then around the platen in a curved path, means which afford a shifting of the platen relatively to said directing means so that the curved portion of the work sheet may be straightened to accord with and lie in substantially the same plane as the said flat portion thereof, a line spacing wheel carried by the platen, and a line spacing pawl carried by the carriage and co-operative directly with the line spacing wheel when the platen is in the normal position, the line spacing wheel being shiftable with the platen out of co-operative relation with said pawl when the platen is shifted from the normal position.

61. In a typewriting machine, the combination of a carriage, a rotative platen carried thereby, means for directing a plurality of superposed layers of paper and an interleaved transfer sheet substantially in a flat condition to the platen and then around the platen in a curved path, means which afford a shifting of the platen relatively to said directing means so that the curved portions of the layers and the transfer sheet may be straightened to accord with and lie in substantially the same plane as the said flat

portions thereof, hand actuated means for effecting a backward displacement of the transfer sheet relatively to the layers of paper when the paper and transfer sheet are straightened as specified, a line spacing wheel carried by the platen, and a line spacing pawl carried by the carriage and coöperative directly with the line spacing wheel when the platen is in the normal position, the line spacing wheel being shiftable with the platen out of coöperative relation with said pawl when the platen is shifted from the normal position.

62. In a typewriting machine, the combination of a carriage, a platen frame pivoted thereto, a platen shaft carried thereby and mounted to turn in said platen frame, a platen mounted on said platen shaft, finger wheels on said platen shaft, and paper feeding and guiding devices carried by the carriage and relatively to which said platen and platen frame are adapted to be shifted by a pivotal movement of the platen frame, the platen moving to and being normally maintained in coöperative relation with said paper feeding and guiding devices by gravity.

63. In a typewriting machine, the combination of a carriage, a platen frame pivoted thereto, a platen shaft carried thereby and mounted to turn in said platen frame, a platen mounted on said platen shaft, finger wheels on said platen shaft, paper feeding and guiding devices carried by the carriage and relatively to which said platen and platen frame are adapted to be shifted by a pivotal movement of the platen frame, the platen moving to and being normally maintained in coöperative relation with said paper feeding and guiding devices carried by the carriage and relatively to which said platen and platen frame are adapted to be shifted by a pivotal movement of the platen frame, the platen moving to and being normally maintained in coöperative relation with said end of one blank on the work sheet and the first printing line on another blank.

64. In a typewriting machine, the combination of a carriage, a platen frame pivoted thereto, a platen shaft carried thereby and mounted to turn in said platen frame, a platen mounted on said platen shaft, finger wheels on said platen shaft, and paper feeding and guiding devices carried by the carriage and relatively to which said platen and platen frame are adapted to be shifted by a pivotal movement of the platen frame, the platen moving to and being normally maintained in coöperative relation with said paper feeding and guiding devices by gravity, an auxiliary frame pivoted to the platen frame the pivotal center of said auxiliary frame being near the printing line.

65. In a typewriting machine, the combi-

nation of a platen; means for displacing a transfer sheet relatively to said platen, said means comprising a carrier, and a bar detachably connected to said carrier; and means for detachably connecting a transfer sheet to said bar, said last mentioned means comprising a clamping member movable relatively to said bar and coöperative therewith to clamp the transfer sheet to the bar.

66. In a typewriting machine, the combination of a platen; means for displacing a transfer sheet relatively to said platen, said means comprising a carrier, and a bar detachably connected at only one end to said carrier; and means for detachably connecting a transfer sheet to said bar, said last mentioned means comprising a sheath movable relatively to said bar and coöperative therewith to clamp the transfer sheet to the bar.

67. In a typewriting machine, the combination of a platen; means for simultaneously displacing a plurality of transfer sheets relatively to said platen, said means comprising a carrier, a single connecting device on the carrier and by which a plurality of bars are detachably connected to said carrier; and means associated with each bar for detachably connecting a transfer sheet thereto, said last mentioned means comprising a clamping member associated with each of said bars and movable relatively thereto and coöperative therewith to clamp a transfer sheet thereto.

68. In a typewriting machine, the combination of a platen; means for simultaneously displacing a plurality of transfer sheets relatively to said platen, said means comprising a carrier, a pin carried by said carrier, and a plurality of bars mounted one on top of another on said pin and detachable therefrom; and means for detachably connecting a transfer sheet to each of said bars, said last mentioned means comprising a clamping member carried by each bar and coöperative therewith to clamp a transfer sheet to the bar.

69. In a typewriting machine, the combination of a platen, and means for shifting a transfer sheet relatively to the platen, said means comprising a bar, and a sheath pivoted thereto and coöperative with the bar to clamp a transfer sheet thereto and affording a detachment of the transfer sheet from the bar when desired.

Signed at the borough of Manhattan, city of New York, in the county of New York and State of New York, this 12th day of April, A. D. 1915.

ARTHUR W. SMITH.
